INVENTOR.

UNITED STATES PATENT OFFICE.

ANTHONY PARRELLA, OF NEW YORK, N. Y.

DESIGN FOR AN AUTOMOBILE-RADIATOR CORE.

59,976.

Specification for Design.

Patented Dec. 13, 1921.

Application filed March 24, 1921. Serial No. 455,236. Term of patent 7 years.

To all whom it may concern:

Be it known that I, ANTHONY PARRELLA, a citizen of the United States, residing at 524 West 131st street, in the city, county, and State of New York, have invented a new, original, and ornamental Design for Automobile-Radiator Cores, of which the following is a specification, reference being had to the accompanying drawing, forming part thereof.

The figure is a front view of an automobile radiator core showing my new design.

The core consists of diamond shaped apertures, the borders of which are elongated and in rows alternating with rows of normal,

equilateral diamond shaped apertures, the drawing showing the first row as half diamonds having arcuate tops, the second row being normal shaped and the succeeding row, of elongated diamond shaped apertures—all rows of apertures succeeding being alternating rows of normal and elongated diamond shaped apertures.

I claim—

The ornamental design for an automobile radiator core as shown and described.

ANTHONY PARRELLA.
